UNITED STATES PATENT OFFICE.

JOHN A. BOWEN, OF WASHINGTON, DISTRICT OF COLUMBIA, ASSIGNOR OF ONE-HALF TO JOHN B. DICKMAN, OF SAME PLACE.

GARBAGE-RECEPTACLE.

SPECIFICATION forming part of Letters Patent No. 553,640, dated January 28, 1896.

Application filed October 12, 1895. Serial No. 565,461. (No model.)

To all whom it may concern:

Be it known that I, JOHN A. BOWEN, a citizen of the United States, residing at Washington, in the District of Columbia, have invented 5 certain new and useful Improvements in Garbage-Receptacles; and I do hereby declare the following to be a full, clear, and exact description of the invention, such as will enable others skilled in the art to which it appertains to 10 make and use the same.

My invention relates to garbage-receptacles, and has for its object to produce a device wherein the receptacle for the garbage may be conveniently held upon a pivoted 15 panel in a fence or building so that when said panel is closed the receptacle will hang on the inside of said fence or building and when the panel is opened the receptacle will be 20 swung into a position on the outside of the fence or building.

To the accomplishment of the foregoing and such other objects as may hereinafter appear, the invention consists in the construction and combination of parts hereinafter particularly 25 described and then sought to be specifically defined by the claims, reference being had to the accompanying drawings, forming a part hereof, in which—

Figure 1 is a perspective of the invention 30 as applied in use; and Fig. 2 is a vertical section through the same, the opened position of the panel being shown in dotted lines.

In the drawings, the numeral 1 designates a fence or the exposed portion of any suitable 35 building or partition, and 2 a pivoted or swinging panel or door formed to occupy a space cut from said fence so as to close and protect the same. This panel is pivoted by any suitable means—for instance, by the bar 40 3 secured thereto by screws and to the fence by keepers 4 so as to be pivoted in said keepers. At the lower edge of said panel I provide a strip or bead 5 to limit the outward movement of the lower portion of the panel 45 when the same is being closed. At the top of the panel a similar strip 6 is secured for a like purpose. To one face of the panel and at right angles thereto are affixed the supports or brackets 7 which are secured by screws or 50 other suitable means, and are provided with the bearings 8. Within these bearings the

receptacle 9 is pivoted by means of the pivoting pintles or projections 10 which extend from each side of the receptacle, so that the receptacle is always free to swing into an upright position during the swinging movement of the pivoted panel, and thus the spilling of liquid from the receptacle during its movement is prevented.

By the use of this invention the garbage 60 may be readily collected by the collector, who has only to swing the pivoted panel outward by means of the handle thereon, and during its movement the receptacle is constantly maintained in an upright position, so that there 65 is no danger of spilling either the garbage or any liquid which may be in the receptacle. When the receptacle is in its outward position it may be readily swung upon its pivot to dump its contents into the receptacle carried 70 by the collector.

The panel is provided with a suitable handle 11, and a lock and key 12 may be provided if it is desired to secure the panel in its closed position to prevent tampering therewith. 75 The receptacle may be of any suitable nature and is preferably provided with a pivoted cover, as shown. When the panel is in its open position the opening in the fence is practically closed so as to prevent the entrance 80 therethrough of any person.

I have illustrated and described in detail the preferred construction of this invention; but many alterations and changes may be made in the construction of parts without departing from the spirit of the invention.

Having described my invention and set forth its merits, what I claim, and desire to secure by Letters Patent, is—

1. In a garbage receptacle, the combination with a pivoted panel adapted to form a closure, of a support for a receptacle extending at an angle from said panel, and a receptacle pivotally mounted on said support, substantially as described.

2. In a garbage receptacle, the combination with a pivoted panel adapted to form a closure, of a support extending at an angle from one side of said panel, and a receptacle pivoted in said support, substantially as described.

3. In a garbage receptacle, the combina-

tion with the pivoted panel, adapted to form a closure, of parallel supports extending at an angle therefrom, and a receptacle located between said supports and pivoted thereon, 5 substantially as described.

4. In a garbage receptacle, the combination with the pivoted panel, of a support extending at an angle from one side of said panel and provided with bearings, and a receptacle pivoted to swing on said bearings, 10 substantially as described.

5. In a garbage receptacle, the combination with the pivoted panel, of the horizontal

rod or bar pivotally supporting said panel, a stop to limit the movement of the swinging 15 panel, the brackets secured to said panel at right angles thereto and provided with bearings, and the receptacle pivotally mounted on said brackets, substantially as described.

In testimony whereof I affix my signature 20 in presence of two witnesses.

JOHN A. BOWEN.
